(57) **CLAIM**

The ornamental design for a toy storage basket, as shown and described.

DESCRIPTION

FIG. 1 is a perspective view of a toy storage basket showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a perspective view thereof, showing the mat in the basket and the lid of the basket is in an open state; and, FIG. 9 is another perspective view thereof, showing the mat in the basket and the basket closed.

The broken lines depict stitching lines and form part of the claimed design.

1 Claim, 9 Drawing Sheets
